FREDERICK A. FELDKAMP, OF NEWARK, NEW JERSEY.

MULTIPLE-FUSE PLUG.

1,318,653.

Specification of Letters Patent. Patented Oct. 14, 1919.

Application filed March 31, 1919. Serial No. 286,264.

To all whom it may concern:

Be it known that I, FREDERICK A. FELDKAMP, a citizen of the United States, residing at Newark, in the county of Essex and State of New Jersey, have invented certain new and useful Improvements in Multiple-Fuse Plugs; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to improvements in fuse plugs; and the invention has reference, more particularly, to an improved construction of multiple fuse plug.

20 The present invention has for its principal object to provide a very cheap, simply constructed and easily manipulated multiple fuse plug, having the general exterior construction and appearance of a single fuse plug, so that the same may be inserted in the usual manner in a receiving socket connected in the electric circuit to be served, but which is so constructed that its inner end contact button may be successively electrically engaged, upon the performance of a simple operation, with the plurality of fuse elements contained within the interior of the fuse plug body, until all of said fuse elements have been utilized or consumed.

25 Another object of the invention is to provide a very cheap, simple efficient and easily assembled socket-thread engaging contact element, which eliminates, by its use, the necessity of employing the expensive male thread shells with which fuse plugs are ordinarily provided.

30 Other objects of the present invention, not at this time more particularly enumerated, will be clearly understood from the following detailed description of the same.

35 With the various objects of the present invention in view, the same consists, primarily, in the novel construction of multiple fuse plug hereinafter set forth; and, furthermore, the invention consists in the novel arrangements and combinations of the various parts, as well as in the details of the construction thereof, all of which will be hereinafter more fully described and claimed.

The invention is clearly illustrated in the accompanying drawings, in which:—

Figure 1 is a side elevation of my novel construction of multiple fuse plug; Fig. 2 is an inner end elevation of the same; and Fig. 3 is an outer end elevation of the same: 60

Fig. 4 is a longitudinal transverse section, taken on line 4—4 in said Fig. 2, said view being drawn on an enlarged scale; Fig. 5 is a cross-section taken on line 5—5 in said Fig. 4; Fig. 6 is a cross-section taken on line 6—6 65 in said Fig. 4; and Fig. 7 is a cross-section taken on line 7—7 in said Fig. 4.

Fig. 8 is a part side elevation and part longitudinal transverse section taken on line 8—8 in said Fig. 2 to show the arrangement 70 of the novel socket-thread engaging contact element.

Fig. 9 is a view similar to that shown in Fig. 8, but in which the ordinary male thread shell is substituted for the novel 75 socket-thread engaging contact element of Fig. 8.

Fig. 10 is a cross-section, similar to that shown in Fig. 5, but illustrating a modified form of construction and mounting of an 80 anchor ring with which all the fuse elements are connected and in part supported.

Similar characters of reference are employed in all of the hereinabove described views, to indicate corresponding parts. 85

Referring now to the said drawings, the reference character 1 indicates a fuse plug body, which is constructed of some suitable insulating material, such as fiber, porcelain, or the like. The outer end of said plug body 90 is provided with an outwardly extending annular shoulder 2. Associated with the inner end of said fuse plug body 1 is a movable member or head 3 which is also constructed of some suitable insulating material. 95

Said movable member or head 3 is provided with a metallic contact button 4 centrally disposed and exposed on the outer side of the same. Said contact button 4 is 100 provided with a shank-portion 5 which extends rearwardly through said movable member or head 3. Arranged on the rearward side of said movable member or head 3 is a radially off-set contact arm 6, through 105 which the said shank-portion 5 extends so that its end may be riveted over said contact-arm to both mechanically and electri-

18, and shank portions 20 which pass through said partition members 17 so as to enter said fuse chambers or compartments 16. Said shank portion 20 may be threaded to screw through said partition members, or they may be otherwise secured to said partition members, as may be deemed most convenient. Secured to the fuse chamber or compartment penetrating ends of said shank portions 20 are fuse elements or wires 21, which respectively extend forwardly through the interior of said fuse chambers or compartments in alinement with the longitudinal axes thereof.

Countersunk in the face of the outer end of said plug body 1 is an anchor ring 22 provided in connection with its inner periphery with inwardly turned anchor tongues or lugs 23, which respectively enter the outer ends of said respective fuse chambers or compartments 16, and to which are secured by means of solder 24 or other desired means, the opposite ends of said fuse elements or wires 21, so that each fuse element or wire is both mechanically and electrically connected with said anchor ring.

Said plug body 1 is provided, in its outer cylindrical surface, with a longitudinally extending channel or groove 25 in which is fixed a socket-thread engaging contact element 26, which is provided with a series of outwardly projecting longitudinally disposed serrations 27 adapted to conform to the thread channels of the screw-threaded female contact shell with which the receiving socket in which the fuse plug is to be screwed is provided. Said contact element 26 has a tail piece 28 which passes through an opening 29, provided therefor in the plug body, into engagement with said anchor ring 22, the body of which it penetrates, and to which it is secured by solder 30, or otherwise, thereby connecting said contact element 26 both electrically and mechanically with said anchor ring 22.

Each fuse chamber or compartment 16 is adapted to be filled with a desirable filler powder, or other similar material, such as is commonly used in fuse devices, and which is adapted to absorb the vapors generated by the burning of the fuse element or wire, although in order not to interfere with the clear illustration of the mechanical structure of my invention, graphic illustration of such filler has been omitted from the drawings. The disposition of the fuse elements or wires in each compartment or chamber 16 is such that the filler powder will entirely surround and envelop the same as well as the anchor tongues or lugs 23 of the anchor ring 22. After the chambers or compartments 16 are filled with the filler powder, the open ends thereof are closed over by an insulator disk 31, which also extends over the outer surface of the anchor

Said fuse plug body 1 is provided with a central longitudinally disposed slideway 12 extending therethrough from its inner end, and terminating toward its outer end in a diametrically enlarged opening 13.

The free end of said stem or rod 11 extends through and is slidably disposed in said slideway 12 so as to enter said enlarged opening 13. Seated in said opening 13, so as to coil about said stem or rod 11 is a compression spring 14. The free end of said stem or rod 11 is provided with screw threads to permit the engagement therewith of a nut-member 15, against which the outer end of said spring 14 bears, so as to exert an inward thrust upon said stem or rod 11 to draw up and maintain said movable member or head 3 in normal closed relation against the inner end of the plug body 1.

The said plug body 1 is bored from its outer end to provide a plurality of longitudinally extending fuse chambers or compartments 16, the same being disposed parallel to and arranged about the longitudinal axis of the plug body. Said fuse chambers or compartments 16 are open at the outer end of the plug body, but are closed at their inner ends by means of traverse partition members 17, preferably forming an integral part of the plug-body. Formed in the inner end of said plug body 1, so as to be respectively alined with the respective fuse chambers or compartments 16, are a plurality of depressed seats or sockets 18, the inner ends of which terminate at the partition members 17. Countersunk in said depressed seats or sockets 18 are fuse anchoring devices, comprising heads 19 disposed in the bottom of said depressed seats or sockets

ring 22. A cap 32 is then placed over the outer end of the plug body 1 to hold said disk 31, the marginal edges 33 of said cap being turned over and around the annular 5 shoulder 2, to hold the cap in secured assembled relation to the plug body 1.

Normally the movable member or head is drawn back and maintained against the inner end of the plug body 1, in which position 10 it so disposes the contact member 7 that the same enters a seat or socket 18, so that its free end electrically engages a head 19 of the fuse anchoring device located therein. When thus arranged the fuse plug is ready 15 for use, and may be screwed into a receiving socket connected in the electrical circuit to be served thereby. When screwed into such receiving socket, the contact element 26 electrically engages the threaded contact 20 shell of such receiving socket, while the contact button 4 electrically engages the central contact element of such receiving socket. The fuse plug is thus electrically connected in the circuit to be served there- 25 by, so that the current flows into said contact button 4 and is conducted through the shank-portion 5 and contact arm 6 to the contact element 7. The contact element 7 engaging a head 19 of a fuse anchoring de- 30 vice passes the current into the fuse wire or element connected with the engaged fuse anchoring device. The current passes through the fuse wire or element into the anchor-ring 22, and thence through the contact element 26 to the contact shell of the receiving socket, thus completing the circuit 35 through one of the fuse wires or elements of the fuse plug, while the remaining fuse wires or elements are cut out of such circuit.

40 When the particular fuse wire or element thus connected in circuit is burned out or blown, the fuse plug is unscrewed from the receiving socket, and the movable member or head 3 is moved longitudinally outward 45 against the tension of the spring 14, which movement withdraws the contact member 7 from engagement with the blown fuse anchoring device, and retracts the same from the seat or socket 18, as illustrated by the 50 dotted lines in Fig. 4 of the drawings. Now the said movable member or head 3 may be given a partial rotation on the stem or rod 11, to locate said contact member opposite the next adjoining seat or socket 18, and then released to permit the spring 14 to draw in the stem or rod 11, and thus return 55 the movable element or head 3 to normal position against the end of the plug body 1. As said movable element or head thus moves 60 back to said normal position, the contact element 7 enters said last mentioned seat or socket 18 to electrically engage the fuse anchoring device located therein, thus electrically connecting a new fuse element or 65 wire between the contact member 7 and the

contact element 26, so that the fuse plug may be again screwed into the receiving socket to electrically insert the new fuse element or wire in the circuit to be served. These operations may be repeated until all 70 the fuse wires have been utilized and blown.

One of the advantages which my novel construction of multiple fuse plug provides, lies in the fact, that when the same is screwed into the receiving socket, to connect 75 the same in circuit, not only is the movable member or head 3 forced, by the threaded engagement of the fuse plug with the receiving socket, to maintain a good firm engagement of its contact button 4 with the central contact element of the receiving socket, but also the contact element 7 is likewise held firmly locked in engagement with a fuse anchoring device, since the head is ob- 80 structed by the receiving socket from any 85 accidental outward movement. Furthermore, when screwed into place the movable member or head 3 is concealed within the receiving socket, and cannot be tampered with so that the fuse plug cannot be manipulated 90 or otherwise disturbed while it is screwed home into the receiving socket, and consequently idle or mischievous tampering with the fuse plug mechanism cannot be accom- 95 plished, without entirely removing the fuse plug.

The fuse plug body 1 may be provided on its exterior surface, adjacent to said movable member or head 3, with suitable indicating marks 34 denoting the position of 100 the respective fuse chambers and their fuse elements, and in like manner the exterior surface of said movable member or head 3 may be provided with a suitable indicating mark 35 denoting the position of said contact member 7, so that by selectively regis- 105 tering the mark 35 with one of the marks 34, the contact member 7 may be brought into electrical contact with a desired fuse ele- 110 ment or wire, to set the fuse plug ready for operation.

While I have illustrated in the drawings a fuse plug body 1 possessing four compartments, each containing its individual fuse element or wire, it will be clearly under- 115 stood that the number of such compartments and fuse elements or wires may be decreased or increased within practical limits.

Referring now to Fig. 9 of the drawings, I have illustrated therein the novel construction of fuse plug body provided with an ordinary male screw threaded contact shell 36, in place of the contact element 26 above described. Said shell 36 is provided with a tongue 37 which is passed through an opening in the body 1, so as to engage 120 said anchor ring 22 to electrically connect said shell 36 with said ring 22.

Referring to Fig. 10 of the drawings, I have shown a slightly modified construction 130

and arrangement of anchor ring device. Instead of using the flat anchor ring 22 having the anchor tongues or lugs 23, I provide a flat strip bent edgewise into ring shape, and 5 then countersunk edgewise in the outer end of said plug body 1, so as to intersect each fuse compartment 16, thus providing an anchor ring 38. Each portion of the anchor ring 38, which cross the ends of the compartments 16 is indented as at 39 to provide 10 a seat for the end of the fuse elements or wires which, as thus positioned, are soldered in connected relation to the anchor ring. The said indentations are so positioned as to aline themselves with the axes 15 of the compartments 16, so as to maintain the fuse elements or wires centrally located therein. The tail piece 28 of the contact element 26 is notched in its end to straddle 20 said anchor ring 38, so that the same may be both electrically and mechanically connected therewith. Aside from the above stated modifications, the novel fuse plug is constructed in the same way, and operates 25 in the same manner as already above described.

I claim:

1. A multiple fuse plug comprising a plug body, a head connected with the inner end 30 of said plug body so as to be capable of movement relative to said plug body, a plurality of fuse elements within said plug body, an exterior contact element on said plug body, a common means for electrically 35 connecting said fuse elements with said exterior contact element, an exterior contact button carried by said movable head, and means controlled by the movement of said head for electrically connecting any one of said 40 fuse elements with said contact button.

2. A multiple fuse plug comprising a plug body having a plurality of compartments, a head connected with the inner end of said plug body so as to be capable of movement 45 relative to said plug body, a fuse element in each compartment, an exterior contact element on said plug body, a common means for connecting the outer ends of said fuse elements with said exterior contact element, 50 a fuse element anchoring device connected with the inner end of each fuse element, an exterior contact button carried by said movable head, and means controlled by the movement of said head for electrically engaging 55 a fuse element anchoring device for electrically connecting any one of said fuse elements with said contact button.

3. A multiple fuse plug comprising a plug body having a plurality of compartments, 60 a movable head connected with the inner end of said plug body so as to be capable of both longitudinal outward movement and rotary movement relative thereto, an exterior contact element on said plug body, a fuse element in each compartment, a common means

for electrically connecting each fuse element with said exterior contact element, a contact button on said movable head, a contact member on the inner side of said head 70 electrically connected with said contact button, and individual fuse anchoring devices respectively connected with the inner end of each fuse element with which said contact member may be selectively engaged by movement of said head.

4. A multiple fuse plug comprising a plug body, an axially aligned stem arranged with said body for longitudinal slidable movement relative thereto and adapted to project from the inner end of said body, a head 80 mounted on the exterior end of said stem, spring means associated with said stem for retracting the same to hold said head normally against the inner end of said body, a plurality of fuse elements within said plug body, an exterior contact element on said plug body, a common means for electrically connecting said fuse elements with said exterior contact element, an exterior contact button carried by said head, and means controlled by the movement of said head for 85 electrically connecting any one of said fuse elements with said contact button.

5. A multiple fuse plug comprising a plug body having a plurality of longitudinal 90 compartments parallel to the axis of said body, an axially aligned stem arranged with said body for longitudinal slidable movement relative thereto and adapted to project from the inner end of said body, a rotatable head mounted on the exterior end of said stem, spring means associated with said stem for retracting the same to hold 95 said head normally against the inner end of said body, an exterior contact element on 100 said body, a fuse element in each compartment, a common means at the outer end of said body for electrically connecting each fuse element with said exterior contact element, an individual fuse element anchoring 105 device connected with the inner end of each fuse element, an exterior contact button carried by said head, and a contact member on the inner side of said head electrically connected with said contact button, said contact member being adapted by manipulation of said head to be selectively engaged with said individual fuse anchoring devices for 110 electrically connecting a desired fuse element between said contact button and said exterior contact element.

6. A multiple fuse plug comprising a plug body having a plurality of longitudinal compartments parallel to the axis of said body, a movable head connected with the 115 inner end of said plug body so as to be capable of both longitudinal outward movement and rotary movement relative thereto, a fuse element in each compartment, an anchor ring connected with the outer end of 120

5 said plug body to which the outer ends of said fuse elements are connected, a contact element embedded in the outer surface of said plug body provided with a plurality of longitudinally alined outwardly projecting serrations adapted to engage the threaded contact shell of a receiving socket, said contact element having a tail-piece extending into electrical engagement with said anchor 10 ring and secured thereto, a contact receiving means at the inner end of each compartment to which the inner ends of said fuse elements are respectively secured, a central exterior contact button on the outer face 15 of said movable head, and a contact member on the inner side of said head, electrically connected with said contact button, said contact member being adapted by manipulation of said head to be selectively engaged with 20 said contact receiving means for electrically connecting a desired fuse element between said contact button and said contact element.

7. A multiple fuse plug comprising a plug body having a plurality of longitudinal compartments parallel to the axis of said body, a movable head connected with the inner end of said plug body so as to be capable of both longitudinal outward movement and rotary movement relative thereto, 25 a fuse element in each compartment, an anchor ring connected with the outer end of said plug body to which the outer ends of said fuse elements are connected, a contact element embedded in the outer surface of 30 said plug body provided with a plurality of longitudinally alined outwardly projecting serrations adapted to engage the threaded contact shell of a receiving socket, said contact element having a tail-piece extending 35 into electrical engagement with said anchor ring and secured thereto, a contact receiving means at the inner end of each compartment to which the inner ends of said fuse elements are respectively secured, a central 40 exterior contact button on the outer face of said movable head, a contact member on the inner side of said head, electrically connected with said contact button, said contact member being adapted by manipulation of 45 said head to be selectively engaged with said contact receiving means for electrically connecting a desired fuse element between said contact button and said contact element, said plug body having an annular laterally projecting shoulder at its outer end, an insulator plate closing the outer ends of said compartments, and a cap extending over said insulator plate and engaged over said shoulder to secure said insulator plate in place.

8. A multiple fuse plug comprising a plug body having a plurality of longitudinal compartments parallel to the axis of said body, said compartments being closed at their inner ends and open at their outer ends, an 55 axially alined stem arranged within said body for longitudinal slidable movement relative thereto and adapted to project from the inner end of said body, a rotatable head mounted on the exterior end of said stem, spring means associated with said stem for retracting the same to hold said head normally against the inner end of said body, a fuse element in each compartment, an anchor ring connected with the outer end of said plug body to which the outer ends of said fuse elements are connected, a contact element embedded in the outer surface of said plug body provided with a plurality of longitudinally alined outwardly projecting serrations adapted to engage the threaded contact shell of a receiving socket said contact element having a tail piece extending into electrical engagement with said anchor ring and secured thereto, a contact receiving means entering the inner closed ends of each compartment to which the inner ends of said fuse-elements are respectively connected, a central exterior contact button on the outer face of said head, a contact member on the inner side of said head electrically connected with said contact button, said contact member being adapted by manipulation of 65

- said head to be selectively engaged with said contact receiving means for electrically connecting a desired fuse element between said contact button and said exterior contact element, an insulator plate arranged over the outer end of said plug body to close the outer ends of said compartments, and a cap extending over said insulator plate and secured to said plug body.
- 10 10. A multiple fuse plug comprising a plug body, a head connected with the inner end of said plug body so as to be capable of movement relative to the latter, a plurality of fuse elements within said plug body, an exterior contact element embedded in the outer surface of said plug body provided with a plurality of longitudinally aligned outwardly projecting serrations adapted to engage the threaded contact shell 15 of a receiving socket, a common means for electrically connecting said fuse elements with said exterior contact element, an exterior contact button carried on the outer face of said head, and means controlled by the movement of said head for electrically connecting any one of said fuse elements with said contact button.
- 15 11. A multiple fuse plug comprising a plug body, an axially aligned stem arranged 20 with said body for longitudinal slidable movement relative thereto and adapted to project from the inner end of said body, a rotatable head mounted on the exterior end of said stem, spring means associated with said stem for retracting the same to hold said head normally against the inner end of said body, a plurality of fuse elements within said plug body, an exterior contact element embedded in the outer surface of said plug body provided with a plurality of 25 longitudinally aligned outwardly projecting serrations adapted to engage the threaded contact shell of a receiving socket, a common means for electrically connecting said fuse elements with said exterior contact element, an exterior contact button carried on the outer face of said head, and means controlled by the movement of said head for electrically connecting any one of said fuse elements with said contact button.
- 25
- In testimony that I claim the invention set forth above I have hereunto set my hand this 27th day of March, 1919.
